UNITED STATES PATENT OFFICE.

NOAH FELLS, OF NEW YORK, N. Y.

PANE-SECURING MEANS.

No. 895,356.

Specification of Letters Patent.

Patented Aug. 4, 1908.

Application filed March 7, 1908. Serial No. 419,749.

To all whom it may concern:

Be it known that I, NOAH FELLS, a citizen of the United States, residing at New York, in the county of New York and State of New York, have invented new and useful Improvements in Pane-Securing Means, of which the following is a specification.

This invention relates to pane securing means and embodies certain improvements in these devices which provide for a simple and cheap clamp for securing together the beveled edges of two panes of glass or walls of wood, the object of the invention being to apply the clamp with as little previous preparation of the panes as possible, as will be more fully described in the following specification, set forth in the claims and shown in the accompanying drawings, where;

Figure 1 is a perspective view of the improved device applied to the corner of two panes of glass. Fig. 2 is a horizontal sectional view of two panes of glass with the device in plan. Fig. 3 is a detail view. Fig. 4 is a sectional view of the two panes showing the opening for the stem of the device.

This device is adapted for use where two panes of glass are beveled and joined to form the corner of a show window or show case where no other agent is used to hold these panes together and it consists of the angle piece composed of the arms 5 and 6 whose inner faces 7 are made at an angle to correspond with the corner formed by the two panes. This angle need not be any special degree, as it is obvious that in the construction of windows and show cases the glass sides are set at various angles. Where these two inner faces would properly meet a semi-circular groove 8 is formed and equi-distant from each of the outer faces of the arms a stem 9 is secured to the angle piece and in the groove 8. The stem is provided at its outer end with the screw threads 10 while it is formed with a reduced portion 11 adjacent to its point of attachment.

The binding or locking of the two panes 12 and 13 is effected by means of a clamping member 14 with a slot 15 for the passage of the stem 9. The ends 16 of this member are turned at angles to correspond with the inner surface of the panes of glass, and to hold the member in place and clamp it against the panes a nut 9^a on the stem is provided to effect the clamping. One very costly feature

heretofore in the use of these devices has been the perforation or preparation of the panes for the passage of the stem 9 and it has been customary to form a perforation in the angle formed by the panes by making a groove in each angular face, but this is not only costly but it is difficult to cause the two grooves to register.

The present invention provides for a single groove or opening 17 cut in the beveled face of the pane 13, but it is obvious that either beveled face may have the groove and it is necessary to off-set the stem 9 to permit it to pass through this perforation on one side of the center of the juncture. To provide for this off setting the arm 5 is reduced in thickness, or in other words, where the inner face of this arm 5 would ordinarily occupy the dotted line 18 of Fig. 3, the arm is reduced and when fitted on the angle of the glass panes it consequently shifts the stem 9 to one side of the center of the angle and in position to occupy the groove in the pane 13. This groove or perforation need be very small or only large enough to admit the reduced part of the stem and the groove 8 readily permits of the shifting of the angle piece where the ordinary angular corner would not.

The reduction of the arm 5 is so little that a casual observer would not notice the difference between the size of the two arms and when the edges of the panes are properly beveled no additional means are necessary to provide for a more effectual juncture.

The locating of the groove 8 in the angle of the two faces of the arms prevents any fracture of the corner of the panes in consequence of the pressure exerted by the clamping member 14 in connection with the angle piece as the arm 6 shifts the glass 13 towards the pane 12 and throws the stem 9 into its groove in the beveled edge of the pane 13 thus making a close and solid joint.

What I claim as new and desire to secure by Letters Patent is:

In a device of the class described, the combination with two panes having beveled edges, the edges of one pane having a horizontally disposed groove of an angle piece composed of two arms to lie against the outer faces of the panes and having at the intersection of said arms a semi-circular groove for receiving the edges of said panes, one of said arms being reduced in thickness or offset

from its adjacent arm, a stem engaged with the angle piece and comprising a flattened outer portion and a threaded inner portion, the flattened outer portion being disposed in the groove formed in one of said panes, a clamping member loosely mounted on the stem and having angularly disposed end portions for engaging the inner faces of said

panes, and a clamping nut engaged with the threaded portion of said stem. 10

In testimony whereof I affix my signature in presence of two witnesses.

NOAH FELLS.
